(57) **CLAIM**

The ornamental design for a chair, as shown and described.

DESCRIPTION

FIG. 1 shows a front perspective view of a first embodiment of the chair in accordance with the new design.

FIG. 2 shows a front elevation view of the chair shown in FIG. 1.

FIG. 3 shows a rear elevation view of the chair shown in FIG. 1.

FIG. 4 shows a left side elevation view of the chair shown in FIG. 1.

FIG. 5 shows a top plan view of the chair shown in FIG. 1.

FIG. 6 shows a bottom plan view of the chair shown in FIG. 1.

FIG. 7 shows a front perspective view of a second embodiment of the chair in accordance with the new design.

FIG. 8 shows a front elevation view of the chair shown in FIG. 7.

FIG. 9 shows a rear elevation view of the chair shown in FIG. 7.

FIG. 10 shows a left side elevation view of the chair shown in FIG. 7.

FIG. 11 shows a top plan view of the chair shown in FIG. 7.

FIG. 12 shows a bottom plan view of the chair shown in FIG. 7.

FIG. 13 shows a front perspective view of a third embodiment of the chair in accordance with the new design.

FIG. 14 shows a rear perspective view of the chair shown in FIG. 13.

FIG. 15 shows a front elevation view of the chair shown in FIG. 13.

FIG. 16 shows a rear elevation view of the chair shown in FIG. 13.

FIG. 17 shows a left side elevation view of the chair shown in Figure

FIG. 18 shows a top plan view of the chair shown in FIG. 13; and,

FIG. 19 shows a bottom plan view of the chair shown in FIG. 13.

The right elevation view of the various embodiments of the chair is a mirror image of the left elevation view as shown in FIGS. 4, 10, and 17.
